UNITED STATES PATENT OFFICE.

CLEMENT L. V. MUNDHENK, OF DAYTON, OHIO.

SELF-HEATING SMOOTHING-IRON.

1,171,349.

Specification of Letters Patent.

Patented Feb. 8, 1916.

Application filed April 25, 1914. Serial No. 834,367.

To all whom it may concern:

Be it known that I, CLEMENT L. V. MUNDHENK, a citizen of the United States, residing at Dayton, in the county of Montgomery and State of Ohio, have invented certain new and useful Improvements in Self-Heating Smoothing-Irons, of which the following is a specification, reference being had therein to the accompanying drawing.

This invention relates to self heating smoothing irons and more particularly to that type of iron which employs gasolene for fuel.

The object of the invention is to provide a smoothing iron of this character which will be safe, of a compact character so that it will be easy to handle, and in which the burner and fuel supply will be of such a character that they may be used separately from the iron itself.

To this end it is an object of the invention to mount the several parts constituting the heating device upon a supporting device which can be readily attached to and removed from the iron; to so connect the fuel tank with the supporting device that while the tank will be supported close to the iron the only direct connection will be a comparatively long tube, thereby materially reducing the possibility of the tank becoming unduly heated; and further, to so construct the fuel tank that it will satisfactorily feed the fuel when either in an upright position or an inverted position; and that the loosening of the closure for the opening through which the tank is filled will interrupt the feeding of fuel to the burner, thereby making it impossible to fill the tank while the gas is ignited at the burner.

It is also an object of the invention to so construct the burner and to so arrange the tubes as to distribute the heat to the best possible advantage to the base of the iron and to cause the tubes to be always amply heated.

In the accompanying drawings, Figure 1 is a side view, partly in section and partly in elevation, of a smoothing iron embodying my invention; Fig. 2 is a transverse, sectional view, taken on the line *b b* of Fig. 1 and looking in the direction of the arrows; Fig. 3 is a plan view of the body portion of the iron showing a modified form of burner; Fig. 4 is a side elevation of the

burner mounted on a support and constituting a stove; and Fig. 5 is a detail, perspective view of the convertible support for the iron and for the burner.

60

In these drawings I have illustrated one embodiment of my invention and have shown the same as comprising a body portion or iron proper having a base 1 and an upwardly extending wall or flange 2 arranged about the edge of the iron but spaced a short distance away from the rear end thereof to permit of the forming of a recess or priming cup 3. Mounted upon this body portion and detachably secured thereto is a top plate 4 on which is mounted a handle 5. The top plate is detachably secured to the body portion in any suitable manner. Mounted within the body portion above the base 1 and between the side portions of the wall 2 is a burner 6 which is so arranged that the flame will be directed downwardly against the base 1. The base, as here shown, is thickened near its central portion to provide a more even distribution of the heat. 80 This construction of the base, as well as the manner of securing the top to the body portion thereof, do not form parts of the present invention but are described and claimed in a co-pending application filed April 25, 85 1914, Ser. No. 834,366.

The burner 6 may be of any suitable character and in the present drawings I have illustrated two forms of burner. In Figs. 1 and 2 the burner is in the form of a straight, hollow bar having apertures in the lower wall thereof. This bar is connected at its rear end with a supporting device 7 which is mounted on the wall of the body portion of the iron and which, in the present instance, comprises a plate having its lateral edges converging downwardly and mounted in grooves 8 formed in the edges of a recess which is formed in the rear portion of the wall of the iron. The burner is provided with an inlet port 9 projecting beyond the plate 7 and arranged in alignment with a vapor discharge nozzle 10. This nozzle is connected with a generating tube 11 which is also carried by the supporting device 7 and is connected at its other end with the source of fuel supply. In that form of the burner shown in Figs. 1 and 2 the ends of the generating tube 11 are mounted in the supporting plate 7 above the burner 6 but are bent downwardly on the inner side of the plate to position the

100

95

105

110

body portion of the tube adjacent to the lower edge of the burner where it will come directly in contact with the flame, thereby securing a very efficient heating action. The 5 fuel tank, which is shown at 12, is also carried by the plate 7 and, to this end, the inlet end of the generator tube 11 is provided with a nipple in the form of an elbow 13 to which is secured an upwardly extending tube 14, 10 the upper end of which is mounted in a cap or screw plug 15 and communicates with the interior of the tank through an opening 16 in said cap. The cap is also provided with an air inlet 17 which is controlled by a check 15 valve 18 and is adapted to have connected thereto an air pump by means of which air may be compressed in the tank to feed the fuel to the burner. To enable the fuel to be forced out of the tank by the air which is 20 compressed on top of the fuel a tube 19 is connected to the port 16 and extends downwardly to a point slightly above the bottom of the tank. Thus, practically all the fuel can be forced out of the tank by the air 25 therein but the sediment or impurities which may settle to the bottom will not enter the feed tube. It will be apparent that the unscrewing of the plug or cap 15 will immediately relieve the air pressure within 30 the tank, thereby interrupting the feed of the fuel to the burner and causing the flame to die out. Thus, before the tank can be separated from its cap to enable the same to be filled the fire will necessarily have 35 been extinguished.

In Fig. 3 of the drawings I have illustrated a modified form of the device in which the burner is shown at 20 in the form of an oval tube conforming substantially 40 in its shape to the interior shape of the body of the iron. This burner is also so arranged as to discharge the flame directly against the base of the iron and by giving the burner the oval shape the flame is more evenly distributed 45 over the surface of the iron. In this form of device the generating tube, which is here shown at 21, enters the supporting plate 7 below the level of the burner and extends for substantially its full length 50 about the inner edge of the burner where it is subjected to the full heat of the burner. It is desirable that the burner be of such a character that it can be used independently of the iron as this gives it a much wider 55 range of utility. The removable supporting device 7 permits the whole burner apparatus to be instantly removed from the iron and by merely inverting the burner the flame may be directed upwardly. This, of course, 60 inverts the fuel tank which is mounted in a fixed position with relation to the burner. In order, therefore, that the fuel may still be properly fed to the burner by the compressed air I have provided the opening in 65 the top of the tank 12 with an inwardly ex-

tending boss 22 which projects some distance above the head of the tank when the latter is in an inverted position. Consequently, all sediment and impurities will settle below the upper end of the boss and will not enter 70 the port 16. It will be understood that the feed tube is removable and when it is desired to use the tank in an inverted position the tube is removed. To enable the burner to be used for miscellaneous heating purposes, that is, in the form of a small gasoline stove, I provide a stand which is adapted to receive and support the burner in an operative position with the flame directed 75 upwardly. The stand consists of upper and lower plates 23 and 24 connected by upright members 25 and is of a length substantially equal to or slightly greater than the length of the iron. The upper plate 23 is provided with a longitudinal slot 26 arranged directly 80 above the burner to permit the flame to pass upward therefrom. A spring 27 is supported by the lower plate 24 of the stand and bears against the lower part of the burner. In the present instance this spring is in the 85 form of a leaf cut from the lower member 24 of the stand. The end of the burner projects slightly beyond the end of the slot 26 and when engaged by the spring 27, the end of the burner is forced into engagement with the under surface of the upper plate 23. The supporting device 7 or the nipples mounted therein to receive the ends of the generating tube 11 rest upon the rear portion 90 of the lower plate 24 which is turned 95 up, as shown at 28, to form a rest therefor. Preferably, the rear portion of the plate 24 is provided with a depression or recess 29 which constitutes a priming cup. This stand is preferably mounted upon supporting devices, such as standards 30, which are 100 here shown as detachably secured to the stand. The standards are shown as each formed of a rod of metal bent into the desired shape and having its upper end bent 105 at substantially right angles to the body portion thereof and adapted to enter sockets 31 formed on the under side of the lower plate of the stand. When the iron is being used as such the legs 30 may be removed 110 from the stand and the latter used as a rest or stand for the iron, it being properly shaped for this purpose and the ends of the side bars 25 being extended below and above the receptacle plates 23 and 24 and forming 115 feet upon which the stand is supported, in the one instance, and stops to position the iron upon the rest in the other instance. 120

It will be noted that the tank is connected with the burner only by the supply tube 14 125 and while this tube is so arranged as to support the tank close to the end of the iron, the tank is in no place directly connected with the iron and the burner except through the supply tube 14. This tube being of 130

considerable length and being connected with the top of the tank has opportunity to radiate the heat so that that portion thereof which is secured to the tank is much cooler than that end which is connected with the burner. Further, the upper portion of the tank is filled with air and this, of course, is not materially affected by the heat. As a further safeguard 10 I may provide the tank with a foraminated tube 32 of a diameter substantially equal to the diameter of the opening in the top of the tank and extending from the boss 22 to the bottom of the tank. This 15 tube may be formed of wire gauze and is of such a length that when placed about the boss with its other end in engagement with the bottom of the tank, which is done during the assembling of the tank, it will be held permanently in position. Should the 20 flame reach the open top of the tank in any way whatever this tube would materially reduce the probabilities of the gasoline exploding. This tube 32 is shown in Fig. 4 25 but is omitted from Fig. 1 in order to more clearly show the tube 19.

While I have shown and described one embodiment of the invention it will be understood that this has been chosen for the 30 purpose of illustration only and that I do not desire to be limited to the details of construction shown and described, for obvious modifications will occur to a person skilled in the art.

35 The connecting device between the top plate 4 and the body of the iron, which is shown in Figs. 1 and 3, does not constitute a part of the present invention but forms the subject matter of a separate application 40 for patent filed by me April 25th, 1914, Ser. N. 834,366.

Having thus fully described my invention, what I claim as new and desire to secure by Letters Patent, is:—

45 1. In a device of the character described, a burner adapted to be supported in one position to direct the flame upward and in another position to direct the flame downward, a supporting device rigidly secured 50 to said burner, a supply tube rigidly secured to said supporting device and extending at substantially right angles to said burner, a fuel tank rigidly connected at one end with said supply tube and extending along- 55 side thereof, whereby said tank will be supported in an upright position when the burner is in a position to direct the flame downward and will be inverted when the burner is in a position to direct the flame upward, 60 said tank having means to feed the fuel to the burner when the latter is in either of said positions.

65 2. In a smoothing iron, the combination with a hollow body portion and a burner adapted to be mounted therein, of a fuel

tank having an opening in the upper end thereof, a cap to close said opening, said cap having an outlet port, a supply tube rigidly secured to said cap, communicating with said port, connected with said burner 70 and adapted to support said cap and said tank, and means to support said burner and said supply tube in their proper positions relatively to said body portion.

3. In a smoothing iron, the combination, 75 with a hollow body portion, and a burner mounted therein, of a fuel tank having an opening in the upper end thereof, a screw-threaded cap to close said opening, said cap having an outlet port, and a supply tube 80 rigidly secured to said cap, connected with said burner and adapted to support said cap and said tank in proper relation to said burner, said cap also having a valve-con- 85 trolled air port to permit air to be pumped into said tank, whereby the movement of said tank to disconnect the same from said cap will relieve the air pressure therein and interrupt the feed of the fuel to said burner.

4. In a smoothing iron, the combination, 90 with a hollow body portion having a recess in the wall thereof at one end of said iron, of a burner mounted in said hollow body portion and arranged to direct the flame downward, a supporting device secured to 95 said burner, mounted in said recess and having parts coöperating with said wall to retain the same in proper position relatively thereto, a generating tube carried by said supporting member and extending beneath 100 said burner, a supply tube secured to said supporting member and connected with said generating tube and extending upwardly therefrom, a fuel tank having an opening in the upper end thereof, a cap to close said 105 opening, said cap being rigidly secured to said supply tube and having an outlet port communicating therewith.

5. In a smoothing iron, the combination, 110 with a hollow body portion having a recess in the wall thereof at one end of said iron, of a burner mounted in said hollow body portion and arranged to direct the flame downward, a supporting device secured to 115 said burner, mounted in said recess and having parts coöperating with said wall to retain the same in proper position relatively thereto, a generating tube carried by said supporting device and extending along 120 said burner, a tube secured to said supporting device, connected with said generating tube and extending upwardly therefrom, a fuel tank having an opening in the upper end thereof, a cap to close said opening, said 125 cap being rigidly secured to said supply tube and having an outlet port communicating therewith, a boss extending inwardly about said outlet port, and a tube connected with said outlet port and extending to a point near the bottom of said tank. 130

6. The combination, with a burner, a supporting device to support said burner either in a position to direct the flame upward or in a position to direct the flame downward, a generating tube carried by said supporting device, and extending along said burner, a supply tube secured to said supporting member, connected with said generating tube and extending upwardly therefrom when said burner is in a position to direct the flame downward, a fuel tank having an opening in the upper end thereof, a cap to close said opening, said cap being rigidly secured to said supply tube and having an outlet port communicating therewith, and a tube of foraminous material surrounding said outlet port and extending from said cap to the opposite end of said tank.

7. The combination, with a burner, and a support plate rigidly secured to said burner, of a supply tube rigidly connected at one end to said supporting plate and extending upwardly from said burner, and a fuel tank rigidly secured at its upper end to said supply tube and supported thereby, said parts being adapted to be reversed to permit the flame of said burner to be directed in the opposite direction, and said fuel tank having means to feed the fuel to said burner when said parts are supported in either position.

8. The combination, with a burner, and a supporting plate rigidly secured to said burner, of a supply tube rigidly secured to said supporting plate and extending upwardly therefrom, a fuel tank comprising a removable cap, said cap being rigidly con-

nected to said supply tube and having an opening to connect said tube with the interior of said tank.

9. In a smoothing iron, the combination, with a hollow body portion, of a burner comprising a hollow tube shaped to conform substantially to the interior contour of the body portion of said iron but of smaller size than said body portion, said hollow tube having jet openings in the lower side thereof to direct the flame against the bottom of the body portion of said iron, and a generating tube supported beneath said burner and extending about the inner edge thereof.

10. The combination, with a burner, a supporting device rigidly secured to said burner, a generating tube secured to said supporting device and extending along said burner, and a supply pipe rigidly secured to said supporting device and communicating with said generator, of a fuel tank having an opening in one end thereof, a boss extending inwardly about said opening, a cap to close said opening, a rigid connection between said supply tube and said cap, the latter having an opening to connect said supply tube with the interior of said tank, and a tube removably attached to said cap, communicating with the opening therein and extending into said tank.

In testimony whereof, I affix my signature in presence of two witnesses.

CLEMENT L. V. MUNDHENK.
